FREQUENCY MODULATING DEVICE

Lee de Forest, Los Angeles, Calif.

Application January 25, 1945, Serial No. 574,516

7 Claims. (Cl. 315—58)

1

My invention relates to a method of and apparatus for modulating electric currents, particularly high frequency currents, such as those employed in radio communication equipment or other electrical transmission circuits, for the purpose of imparting to such currents various signal characteristics or voice modulations preparatory to the transmission of such information.

The invention specifically includes a type of electrically variable capacitor whose utility is not necessarily limited to the aforesaid arts. For the purpose of this disclosure I elect to describe a method of frequency modulation but those skilled in the art will readily recognize that the novel principles embodied in my invention may be usefully employed for effecting various kinds of modulation of electric currents and for performing various other functions.

The general object of my invention is to provide an electrically variable capacitor, whose capacitance may be modulated by voltages or currents, particularly those of audio frequency.

Another object is to provide a method of, and means for, producing broad band frequency modulation without employing complicated conventional circuits.

An important object of my invention is to provide an electronic capacitor whose variable capacitance is modulated by alterations in the nature of the medium disposed between the spaced condenser plates.

A further object is to provide an electronic capacitor whose variable capacitance is modulated by the degree of ionization of a gas disposed between the spaced condenser plates.

An important feature of my modulating system is a cathode beam which modulates the capacitance of my capacitor. This allows a very great simplification in frequency modulation transmitter circuits by eliminating the necessity for the various multiplier stages required in conventional modulation equipment.

Another feature of my modulating system is the modulation of the instantaneous capacitance of a condenser whose internal insulation engages an ionized gas.

Other objects and advantages of my invention, as well as a clear understanding of the principles involved therein and practical methods of applying them, will be suggested by the detailed description and claims to follow, taken with the accompanying drawings, in which:

Fig. 1 is a diagrammatical representation of one embodiment of my modulation system as

2

applied to an electrical circuit for the generation of high frequency currents.

Fig. 2 is a transverse sectional view of a tubular electrode, hereinafter referred to as an electron lens, employed for the purposes of the invention.

Fig. 3 is a side elevational view as partially sectioned of the structure shown in plan on the right side of Fig. 1 exemplifying an embodiment employing some of the elements of a cathode-ray tube for the purposes of the invention.

Fig. 4 is a sectional view of the protected condenser plates employed in my electrically variable capacitor.

15 Figs. 5 and 6 illustrate diagrammatically the elements involved as parameters in an analytical determination of the electrical characteristics of my electrically variable capacitor; Fig. 5 shows a region between spaced layers of dielectric which 20 enclose condenser plates and Fig. 6 indicates symbolically the variable conductance of such a region.

Fig. 7 represents a detailed side view of one form of my electrically variable capacitor and 25 illustrates one of the operating principles involved therein.

Fig. 8 is a diagrammatic view of another embodiment of my modulation system including an electrically variable capacitor which is not confined within a cathode-ray tube.

The schematic arrangement shown in Figure 35 1 illustrates a modulation system, as one embodiment of the invention, whose principal components include a radiating circuit 10 for emitting electromagnetic waves produced by an undulatory electrical current whose intensity is increased by a power amplifier tube 20. These 40 electrical undulations are generated in an oscillatory circuit 30 whose resonant frequency is modulated by a capacitor 40 whose capacitance is modulated by a cathode-ray whose deflection is modulated by a control circuit 50.

The radiating circuit 10, which includes an 45 antenna or radiating dipole 12—13 in series with the primary 14 of a radio frequency transformer 15, is inductively coupled by means of the secondary 16 to the output circuit of the power amplifier vacuum tube 20. This output tube 50 has an anode 17 whose electric potential may be supplied by the positive terminal of a battery 18, or other suitable means, whose negative terminal is grounded to the cathode 19. These 55 terminals of the source of direct current and voltage are shunted by a "by pass" condenser

21 which provides a low impedance path for radio frequency currents.

The direct current and voltage supplied by the battery 18 is conducted through the secondary 16 of the radio frequency transformer 15 and delivered to the anode 17 of the power amplifier tube 20, as well as any additional amplifier tubes, since it will be understood that additional amplification may frequently be desirable.

Such supplementary amplifying tubes would be interposed, of course, between the grid 22 of the power amplifier tube 20 and the output of the master oscillator tube 23, whose anode 24 may also receive electric potential from the anode 17 through an intervening voltage-dropping resistor 25 and a high frequency choke-coil 26.

The grid 22 of the power amplifier tube 20 is energized by the anode 24, unless intermediate stages of amplification are introduced. The biasing potential of the grid 22 is controlled by the voltage across a grid-leak resistor 21, which is grounded by connection with the cathode 19. This grid bias is also protected against the direct voltage of the anode 24 by means of a grid condenser 28.

The modulated carrier wave, whose amplification has been described above, is generated by the master oscillator tube 23 and the associated resonant circuit 30 whose high frequency oscillations are modulated by my electrically variable capacitor 40.

This resonant circuit 30 includes a variable capacitance 31 connected in parallel with an inductance 32 which in this instance is illustrated in the form of an arrangement known as a "butterfly" circuit, which is characterized by a very high circuit Q and by the particular combination of the inductance loop 32 and a subtended stator 33, which encompass a rotor 34. The resonant frequency of this oscillatory circuit is dependent, also, upon the adjustment of the capacitance 31 and upon the electrically variable magnitude of the capacitance of the modulating capacitor 40, which is connected in parallel with the capacitance 31.

This resonant circuit 30 energizes a grid 35 of the oscillator tube 23, whose cathode 36 is grounded to the negative terminal of the battery 18. The biasing potential of the grid 35 is provided by the voltage across a grid-leak resistor 37, which is grounded by connection with the cathode 36. The variations of potential on the grid 35 are amplified, of course, by the tube 23, which delivers a modulated voltage signal at the anode 24 to the grid condenser 28 of the amplifier tube 20. This modulated signal voltage is also applied to the resonant circuit 30, since oscillations are thus sustained. Accordingly, the anode 24 is connected to the stator 33, to the inductance loop 32 and, by means of a sliding contact 38, to the rotor 34. A grid condenser 39 protects the grid 35 from the direct potential of the anode 24. This potential is thus applied to both of the condenser plates, or electrodes, 41 and 42 of the modulating capacitor 40.

It is noteworthy that the electrical circuit so far described in detail is electrically complete and self-sufficient for generating and radiating electromagnetic waves whose modulations are provided by the variations of the resonant frequency of the oscillatory circuit 30. The instantaneous value of this resonant frequency is automatically controlled by the instantaneous values of the conductance and capacitance of the capacitor 40,

parameters which are varied by the control circuit 50.

The modulating capacitor 40 may be designed and employed in a variety of ways within the scope of my invention.

A cathode ray is directed between or below the electrodes 41 and 42 which form the condenser plates of my electrically variable capacitor 40, as illustrated in the plan view at the right in Fig. 1 or by the longitudinal side view in Fig. 3. This cathode ray is emitted by an electron gun having a cathode 43, a tubular grid structure 44, a primary anode or electron lens 45 and a secondary anode or collector plate 46 which serves as a target for the cathode-ray. The direct current potential required by the anodes 45 and 46 may be supplied by conventional means, such as a battery 47, whose negative terminal is connected to the cathode 43. Such potentials may be adjusted by appropriate series resistance, as indicated by the numeral 48 interposed between the anode 46 and the positive terminal of the battery 47.

The modulation of the capacitance and conductance of my electronic capacitor is accomplished by modulating the cathode ray. For this purpose I prefer to employ a magnetic field, directed approximately perpendicular to both the cathode ray and the condenser plates 41 and 42, such as that produced by electromagnets 51 and 52 connected in series "aiding" relationship and energized by an electrical current in the control circuit 50. The terminals of the directly coupled windings of the electromagnets 51 and 52 may be connected into any control circuit which provides an undulatory or variable electromotive force, such as the audio frequency output voltage of a microphonic circuit or of an amplifier connected to a microphonic circuit. Other sources of modulating electromotive force, which may be measured, studied, analyzed or utilized by means of my cathode-ray capacitor, include photo-electric cells, X-rays, radio tubes and television. Such modulating electromotive forces may also be employed by substituting an electrostatic field for the electromagnetic field described above, provided that the electrostatic field is directed approximately perpendicular to the cathode ray and parallel to the condenser plates 41 and 42, as by means of parallel plates whose potential difference is supplied by the control circuit 50.

The performance of my cathode-ray capacitor will be described and analyzed with the aid of Figs. 2, 3, 4, 5, 6, and 7.

Fig. 2 illustrates a desirable form for the cross section of tubular electron lens, or primary-anode 45. This oval transverse section has a longitudinal axis A—A which is oriented substantially parallel to the condenser plates 41 and 42 and approximately perpendicular to the direction of the cathode ray. The potential of this primary anode 45 produces an electrostatic field which tends to concentrate the cathode ray into a sword-shaped beam whose larger transverse dimension is parallel to the axis A—A.

As illustrated in Figs. 3 and 7 the direction O—B of this sword-shaped beam may be modulated by the aforesaid deflecting forces, such as those supplied by the magnetic field produced by the electromagnets 51 and 52 whose axial poles are indicated by the reference numeral 53. This modulation of the direction of the cathode ray may be visualized as a variation in the vertical deflection of the sword-shaped beam, as indicated by the deflection from the position O—B to the position

O—C in Fig. 7. The beam is thus caused to swing upwardly, to a greater or lesser degree, into the region between the condenser plates 41 and 42. This deflection is linearly proportional to the intensity of the control current in the electro-magnets 51 and 52. In the absence of such modulation, the upper edge of the undeflected cathode beam is directed between or below the lower extremities 54 of the electrodes 41 and 42, approximately along the longitudinal axis of the modified cathode-ray tube. As illustrated in Figs. 3 and 4, the condenser plates 41 and 42 of my cathode-ray capacitor 40 are preferably enclosed in glass or other suitable insulating material 55 in order to shield them from approaching ions or electrons. The electrical conductors which travel from these plates through the tubular glass shell, as at 56 and 57, in order to provide terminals for electrical connection with an external circuit, also should be encased in suitable insulating material, such as glass or an appropriate thermoplastic substance. These insulated electrical connectors may serve, of course, as supports for the insulated plates 41 and 42, either as illustrated in Fig. 3 or by extending the arms 58 and 59 to engage the opposite sides of the tubular vessel 60.

My cathode-ray capacitor should be incorporated in a tubular vessel 60 which has been highly exhausted of air but may preferably contain a small amount of one of the noble gases, such as neon or argon. This rarefied gas will be ionized by the impact of collision between the electron beam and the gas molecules. The resulting positive ions are too heavy to be deflected very far by the electrostatic or magnetic fields. Consequently, many of these positive ions receive momentum from electron bombardment by the cathode ray which directs them toward the collector plate 46. The remainder of these heavy positive ions drift toward the negative cathode. In the absence of modulation, therefore, an equilibrium distribution of positive ions exists throughout the tubular vessel 60; and the region D—E between the condenser plates 41 and 42 is occupied by a relatively few ions, which are drifting away from the high direct current potential of these plates toward the negative cathode. Such absence of ions in the region D—E indicates the existence of a dielectric of rarefied gas whose dielectric constant partially determines the variable capacitance of the capacitor 40.

The magnitude of this variable capacitance is also dependent upon the presence of a distribution of electrons on the outer surface of the insulation 55. These electron layers 61 and 62 are supported by the electrostatic force of attraction toward the charged condenser plates 41 and 42. Accordingly, my cathode-ray capacitor provides three subordinate condensers C₁, C and C₂, electrically co-acting in series relationship, respectively comprised of the following pairs of conductive elements: 41—61, 61—62 and 62—42, where the elements 61 and 62 each represent the conductive layer of ions-electrons residing upon the outer surface of the insulation 55, as indicated in Figs. 4 and 5.

The capacitance of the pair of conductive elements 41—61 or 62—42 is approximately represented by the conventional formula

$$(1) \quad C = KA/4\pi D$$

where D represents the distance between two parallel conducting planes whose area is A separated by electrical insulation whose dielectric constant is K. This constant is of the order of 7 to 9 for

glass, as in condenser C₁ or C₂, and approximately unity for the un-ionized gas dielectric in condenser C. The distance D is relatively smaller for C₁ and C₂, perhaps $\frac{1}{2}$ inch, for example, as compared with $\frac{1}{8}$ to $\frac{1}{4}$ inch between the elements 61 and 62. Hence the ratio C₁/C or C₂/C is of the order of 100, since either of the plates 41 or 42 is shielded on each side by a layer of ions-electrons, thus doubling the effective area.

10 The total capacitance of the series combination of condensers C₁, C and C₂ is approximately represented by

$$(2) \quad C_t = \frac{CC_1}{2C+C_1}$$

15 since C₁=C₂ if the thickness of the insulation 55 is uniform, if the condenser plates 41 and 42 have the same area, etc., as illustrated in Figs. 4 and 5.

20 The foregoing description of the state of equilibrium existing in the unmodulated cathode-ray capacitor may be extended by considering the leakage conductance through the condenser C, as provided by the transverse conductance of the cathode ray whenever it is deflected from the normal position O—B to O—C, as indicated in Fig. 7, or from F toward D, as identified in Fig. 4. This leakage conductance

$$30 \quad G = \frac{1}{R}$$

is associated with the indicated variable resistance R identified in Fig. 6 by the numeral 65.

The elements of the cathode-ray capacitor, represented schematically in Fig. 6, now include 35 the series arrangement of condensers C₁, C and C₂ and the resistance R connected in parallel with the capacitance C. The impedance of this series-parallel arrangement will be radically altered whenever the sword-shaped cathode plate 40 is deflected or modulated. For example, if the beam is deflected upwards, the region DE will become highly conductive as a result of the positive ions produced by the bombardment of 45 gas molecules by the deflected beam. Alternatively, if the beam is deflected downwardly, the region DE will become electrically non-conductive as the positive ions are repelled from this region by the potential of the condenser plates 41 and 50 42.

55 The cathode-ray capacitor will provide more effective modulation if the capacitance C₁ is designed relatively larger than the capacitance C, e. g., the insulation 55 should have a minimum thickness, etc.

The effectiveness of the cathode-ray capacitor for modulation purposes may be approximately evaluated. For example, suppose that C₁ has a 60 value of 99 micro microfarads and C has a value of one micro microfarad; then the total impedance of the cathode-ray capacitor will be decreased one hundred fold whenever the cathode-ray is deflected into the region DE between the condenser plates 41 and 42.

65 Another concept may be introduced by considering the cathode-ray capacitor as representing a simple condenser shunted by a resistance R. The impedance of this combination may be written

$$70 \quad (3) \quad Z_t = \frac{-jRX}{R-jX} = \frac{R}{(1+R^2w^2C_3^2)^{\frac{1}{2}}}$$

where C₃ is the capacitance of the condenser plates 41 and 42, encased in insulation, such as glass, and R is inversely proportioned to the area

a_1 of the layer of partially ionized gas lying between the condenser plates 41 and 42.

Equation 3 may be approximately expressed in the form

$$Z_1 = \frac{1}{wC_3 + a_1 b}$$

where b is the conductance per unit of ionized area a_1 , depending on the nature of the gas, the degree of its ionization and the inverse thickness of the layer of partially ionized gas between the condenser plates 41 and 42. The angular velocity $w = 2\pi f$ if f symbolizes the frequency of the oscillatory current. With a given voltage and cathode temperature, the tubular vessel 60 will contain a gas whose degree of ionization is constant.

The ionized area a_1 is a variable determined by the deflection of the ionizing cathode beam. The ionized area a_1 is therefore proportional to the intensity of the current in the control circuit 50, if the electromagnets 51 and 52 are employed, or, alternatively, proportional to the audio frequency potential difference impressed on the deflecting plates of the tube by the control circuit 50 if an electrostatic field is employed instead of a magnetic field for deflecting the cathode beam. The total impedance of the cathode ray capacitor is therefore inversely proportional to the intensity of the current in the control circuit or inversely proportional to the potential difference impressed on the deflecting plates by the control circuit. An approximately linear relationship exists, therefore, between the modulating force and the resulting modulation.

Alternatively, if the cross section of the cathode beam normally fills the inter-electrode region DEF, this cross section may be modulated by the control circuit 50 in order to modulate the ionized area a_1 . Various means of reducing this cross section may be employed. For example, the potential of the primary anode 45 or the control grid 44 may be modulated by the control circuit 50. In this case the total impedance of the cathode-ray capacitor is increased, rather than decreased, in proportion to the applied voltage.

Another alternative embodiment of my cathode-ray capacitor is illustrated in Fig. 8, which shows a tubular vessel 70 containing a rarefied gas and having a constriction which may be flattened, if desired, and partially surrounded by two external condenser plates 71 and 72 for the purpose of modulating the current in a transmission circuit 100 such as that indicated schematically by the block diagram.

The cathode beam, which modulates the capacitance of this cathode-ray capacitor, is generated by a cathode 73, represented by a coiled filament, and concentrated by a control electrode or grid 74 and directed through a constricted portion 75 of the tubular vessel 70 toward an anode or collector plate 76 whose potential is supplied through a high frequency choke coil 77 and a series resistance control 78 by a suitable voltage supply such as the positive terminal of a battery 79.

The transmission circuit 100 is indicated in Fig. 8 by a block diagram labeled Frequency modulated (F. M.) oscillator 101 whose resonant frequency is determined by the variable capacitance of condenser plates 71 and 72. This oscillator 101 delivers a frequency modulated current to a radiating dipole 102-103.

The capacitance of the cathode ray capacitor is modulated by the degree of ionization of the

rarefied gas in the tubular vessel 70. This degree of ionization may be modulated in several ways; two methods will be described; the first method utilizes a grid control circuit 80, shown on the left side of Fig. 8; the second method utilizes a plate control circuit 90 shown on the lower right side of Fig. 8.

The grid control circuit is connected between the cathode 73 and the control grid 74. The audio frequency potential difference between the cathode 73 and the grid 74 is provided by an audio amplifier 81 whose input circuit includes a microphone 82. The direct current potential difference between the cathode 73 and the grid 74 is provided by a battery 83 connected in parallel with a variable resistance 84. This potentiometer arrangement provides a negative biasing potential to the grid 74, which is protected from the direct current potential of the output circuit of the amplifier 81 by interposing a grid condenser 85 in series with the grid 74.

In the foregoing method, the degree of ionization of the rarefied gas in the tubular vessel 70 is modulated by the variable potential of the control grid 74.

In the following alternative method, the potential of the plate 76 is employed for modulating the degree of ionization of the rarefied gas. This potential is controlled by a so-called Heising circuit 90, comprising an audio amplifier triode tube 91, connected in parallel with the ionized gas tube 70, and an audio amplifier 92 whose input circuit includes a microphone 93. The anode potential of the modulator tube 91 may be supplied by the plate 76. The cathode of the tube 91 is connected to the negative terminal of the battery 79.

The modulation from the microphone 93 is amplified by the amplifier 92 and delivered to the cathode and grid of the triode 91 whose anode controls the audio frequency potential of the plate 76 of the ionization tube 70.

The capacitance of the cathode-ray capacitor is thus modulated by the control circuit 90, which modulates the degree of ionization of the rarefied gas in the ionization tube 70.

Additional methods of controlling the ionization of the gas and thus modulating the capacitance of the cathode-ray capacitor are suggested by the foregoing principles and concepts.

For example, I may employ a voice modulated coaxial magnetic field for directly controlling the space-charge density of the cathode beam. This may be accomplished by positioning the longitudinal axis of a solenoid substantially coincident with the cathode ray and energizing the solenoid with the voice modulated control current, in order to modulate the capacitance of the cathode-ray capacitor.

As a second example, I may employ a magnetic field directed through the constricted portion 75 of the ionization tube 70, i. e., directed perpendicular to the cathode beam therein, and modulate the intensity of this transverse magnetic field by means of an amplifier which receives voice modulations from a microphone and delivers a modulated control current to the electromagnets which provide the aforesaid transverse magnetic field. The space charge density of the cathode beam would thus be modulated and the capacitance of the cathode-ray capacitor correspondingly modulated.

By any of the various methods disclosed herein it will be seen that I am able to directly control the instantaneous frequency of a modulated carrier wave and to effect broad band frequency

modulation without the interposition of complicated circuits comprising several multiplier stages.

Other adaptations of the invention may be employed for various purposes other than frequency modulation. Since the preferred form of my invention, which is described herein in specific detail for the purpose of disclosure and to illustrate the principles involved, will suggest to those skilled in the art various changes, modifications and substitutions that do not depart from my underlying concepts, I reserve the right to all such changes, modifications and substitutions that properly come within the scope of my invention.

I claim as my invention:

1. In a variable capacitor, the combination of: a pair of spaced electrodes; a dielectric material between said electrodes; an ionizable dielectric medium between said electrodes; means for directing a stream of electrons through said ionizable medium to effect ionization thereof; and means for deflecting said stream of electrons relative to said electrodes to vary the extent to which it is interposed between said electrodes whereby to vary the degree of ionization of the ionizable medium between said electrodes.

2. In a variable capacitor, the combination of: a pair of spaced electrodes; means for directing an electron beam through the space between said electrodes; and means for deflecting said electron beam relative to said electrodes to vary the amount of the space between said electrodes which is occupied thereby.

3. In a variable capacitor, the combination of: a pair of spaced electrodes; an ionizable medium in the space between said electrodes; means for directing an electron beam through the space between said electrodes to ionize said medium; and means for deflecting said electron beam relative to said electrodes to vary the amount of said ionizable medium between said electrodes which is ionized thereby.

4. In a variable capacitor, the combination of: a pair of spaced electrodes; means for generating a stream of electrons; means for directing said stream of electrons through the space between said electrodes in a fan-shaped beam lying substantially in a plane intermediate said electrodes; and means for deflecting said electron beam in 50

said plain to vary the amount of the space between said electrodes which is occupied thereby.

5. In a variable capacitor, the combination of: a pair of spaced, parallel electrodes; means for normally directing an electron beam parallel to said electrodes adjacent one edge thereof; and means for deflecting said electron beam into the space between said electrodes to vary the capacitance of said capacitor.

6. In a variable capacitor, the combination of: a pair of spaced electrodes; a dielectric material enclosing at least one of said electrodes; means for directing a stream of electrons through the space between said electrodes; and means for deflecting said stream of electrons in a direction transverse to a reference line extending between said electrodes so as to vary the dielectric characteristics of the space between said electrodes.

7. In a variable capacitor, the combination of: a pair of spaced electrodes; a dielectric material enclosing at least one of said electrodes; an ionizable dielectric medium between said electrodes; means for directing a stream of electrons through said medium to effect ionization thereof; and means for deflecting said stream of electrons in a direction transverse to a reference line extending between said electrodes so as to vary the degree of ionization of said ionizable medium in the space between said electrodes, whereby to vary the capacitance of said capacitor.
